CORPORATION OF PENNSYLVANIA

MERCURY-ARC RECTIFIER

Application filed January 28, 1930, Serial No. 423,988, and in Germany October 13, 1927.

Our invention relates to improvements in mercury-arc rectifiers, and more particularly to large rectifiers of high capacity.

It is well known in the art that at the cathode of mercury-arc rectifiers fifteen to twenty times the quantity of mercury vapor is developed which is needed for carrying through the electric processes. This excess of vapor is liable to have an adverse effect upon the discharge in the rectifier if it is not condensed in the condensing equipment which is a constituent of all large rectifiers. The cooling devices known for this purpose are all based upon the principle to provide cooling surfaces in the path of the vapor upon which the vapor should precipitate itself in the form of drops. It is hereby assumed that the mercury vapor would seek out such surfaces with avidity and would forthwith condense upon them.

Our invention is on the other hand based upon the observation that the mercury vapor ascending from the cathode of mercury-arc rectifiers when the output of the rectifiers per unit of volume is considerably increased assumes different qualities owing to the concentration or crowding together of the heat development into smaller spaces; the vapor no longer leaves the cathode chamber in a saturated state, as assumed up to now, but in a superheated state and when dealing with such a superheated mercury vapor the known cooling arrangements fail altogether or are unable to fulfill their object in a satisfactory manner. According to our invention the vapor developed at the cathode of large high-capacity rectifiers is therefore first brought to saturation temperature and saturation pressure and then only condensed.

With this end in view we provide in the rectifier besides the usual cooling surfaces serving for the condensation of the vapor further special cooling surfaces which first cool the superheated vapor. The cooling equipment of the rectifier according to our invention thus consists of a precooler arranged as closely as possible to the cathode and which may have any per se known shape, and a condensing chamber, likewise of known shape, for instance, into which the vapor does

no longer enter in the superheated condition, however.

An embodiment of our invention is illustrated in the drawing affixed to this specification. The example shows a large high-capacity rectifier equipped with a precooling and a condensing device in vertical section.

Referring to the drawing it will be observed that the steel rectifier tank 1 contains the customary mercury cathode 2 at the bottom and above it the anodes 3 placed near the side walls of the tank. Above the cathode there are provided cylindrical cooling members which might, however, be replaced by cooling coils, straight tubes or pocket-shaped coolers. Through these cooling cylinders, an inner cylinder 4 and an outer cylinder 5, ascends vertically the superheated mercury vapor developed at the cathode, preferably without being obstructed in any way. Such an arrangement, offering as little as possible resistance to the flow of the vapor, is necessary because, as well known, the mercury vapor escapes from the cathode at a very high speed which may amount up to 200 meters per second.

The cooling members should extend as closely as possible down toward the cathode to enable them to catch the superfluous vapor as completely as possible and only give the necessary passage free for the arc directed from the cathode towards the anodes. Preferably the width of the cooling cylinders should exceed the width of the cathode.

Above these cooling cylinders 4, 5 serving a new purpose, viz. the cooling of the superheated vapor down to saturation temperature and pressure, there is located the condensing chamber proper 6. Here the vapor is given an opportunity to expand into spaces in which there are located larger cooling surfaces upon which the saturated vapor is able to condense. The design of these cooling surfaces does not per se form part of our invention, particularly in view of the fact that condensing apparatus in rectifiers is known in various designs; the essential feature of our invention is that the cooling spaces are so located that the mercury vapor is obliged to enter the cooling chamber and

100

not the chambers in which the anodes are located.

In this way the anode chamber 7 is kept free from superheated mercury vapor of excessively high vapor pressure as well as of saturated vapor which might then condense at wrong places.

Provisions are furthermore made to keep the condensate formed in the condensation chamber 6 away from the anode chamber. This may for instance, be effected in known manner by making use of the specific gravity of the condensate and separating it from the vapor by means of baffles or deflector plates 8.

It is a further essential feature of our invention that these baffle plates also separate the anode chamber in a drip-proof manner from the cooling and precooling chambers and the condensing chamber.

In our improved cooling equipment in which there are provided two cooling chambers, a precooling chamber which receives the superheated mercury vapors emanating from the cathode and cools them as far as possible down to the saturation temperature without condensing them, and a second cooling chamber which receives the saturated vapors and condenses them, the requirements naturally differ, with which the two cooling chambers have to comply, in view of the different natures of the mercury vapors treated in them. According to our invention the two cooling chambers should not only be differently dimensioned as regards their size but they should also be cooled to a different extent. The first cooling chamber in which the superheated vapor is cooled should, for instance, be subjected to powerful cooling while the second cooling chamber in which the saturated vapor is condensed should be maintained at a slightly higher temperature.

When observing the above described conditions it has been found that in the operation of a large high-capacity rectifier equipped with the new cooling device no condensation is noticeable at the precooling surfaces but that the vapor is precipitated in the form of drops only in the condensation chamber proper. In this way any interference by the mercury vapor with the discharge process taking place within the rectifier is effectively prevented and the output of the rectifier per unit of volume can be increased considerably.

It has also proved advantageous to effect the evacuation of the rectifier between the precooling and the condensing chamber, by, for instance, letting the evacuation pipe 9 leading to the vacuum pump open into the rectifier above the precooling device.

It will be understood that various changes and modifications in the structure of our improved rectifier may be made without de-

parting from the spirit of our invention or the scope of the appended claims.

We claim as our invention:

1. A high-capacity mercury-arc rectifier comprising an evacuated tank, a mercury cathode centrally located in the bottom thereof, a plurality of anodes disposed around the central portion of the space within the tank, a cooling means constituting a condensing chamber at the top portion of said tank, the rectifier being of such design and rating that the mercury vapor developed at the cathode is normally superheated, and a second cooling means constituting a precooling chamber in the center of the space within the tank for normally cooling said superheated mercury vapor to substantially the saturation temperature and pressure before it reaches said condensing chamber, characterized by protective walls for separating the space in which the anodes are located from the precooling and condensing chambers, so that the superheated as well as the saturated mercury vapor is kept away from it.

2. A high-capacity mercury-arc rectifier comprising an evacuated tank, a mercury cathode centrally located in the bottom thereof, a plurality of anodes disposed around the central portion of the space within the tank, a cooling means constituting a condensing chamber at the top portion of said tank, the rectifier being of such design and rating that the mercury vapor developed at the cathode is normally superheated, and a second cooling means constituting a precooling chamber in the center of the space within the tank for normally cooling said superheated mercury vapor to substantially the saturation temperature and pressure before it reaches said condensing chamber, characterized by an outlet means for effecting the evacuation of the rectifier-tank, said means communicating with the space inside of the tank at a place between the precooling chamber and the condensing chamber.

3. A high-capacity mercury-arc rectifier comprising an evacuated tank, a mercury cathode centrally located in the bottom thereof, a plurality of anodes disposed around the central portion of the space within the tank, a cooling means constituting a condensing chamber at the top portion of said tank, the rectifier being of such design and rating that the mercury vapor developed at the cathode is normally superheated, and a second cooling means constituting a precooling chamber in the center of the space within the tank for normally cooling said superheated mercury vapor to substantially the saturation temperature and pressure before it reaches said condensing chamber, characterized by an unrestricted communicating passage, as wide as possible, between said two chambers, the precooling and condensing chambers being maintained at different tem-

peratures, and protective walls for separating the space in which the anodes are located from the precooling and condensing chambers, so that the superheated as well as the saturated mercury vapor is kept away from it.

4. A high-capacity mercury-arc rectifier comprising an evacuated tank, a mercury cathode centrally located in the bottom thereof, a plurality of anodes disposed around the central portion of the space within the tank, a cooling means constituting a condensing chamber at the top portion of said tank, the rectifier being of such design and rating that the mercury vapor developed at the cathode is normally superheated, and a second cooling means constituting a precooling chamber in the center of the space within the tank for normally cooling said superheated mercury vapor to substantially the saturation temperature and pressure before it reaches said condensing chamber, characterized by an unrestricted communicating passage, as wide as possible, between said two chambers, the precooling and condensing chambers being maintained at different temperatures, and an outlet means for effecting the evacuation of the rectifier-tank, said means communicating with the space inside of the tank at a place between the precooling chamber and the condensing chamber.

5. A high-capacity mercury-arc rectifier comprising an evacuated tank, a mercury cathode centrally located in the bottom thereof, a plurality of anodes disposed around the central portion of the space within the tank, a cooling means constituting a condensing chamber at the top portion of said tank, the rectifier being of such design and rating that the mercury vapor developed at the cathode is normally superheated, and a second cooling means constituting a precooling chamber in the center of the space within the tank for normally cooling said superheated mercury vapor to substantially the saturation temperature and pressure before it reaches said condensing chamber, characterized by an unrestricted communicating passage, as wide as possible, between said two chambers, the precooling and condensing chambers being maintained at different temperatures, protective walls for separating the space in which the anodes are located from the precooling and condensing chambers, so that the superheated as well as the saturated mercury vapor is kept away from it, and an outlet means for effecting the evacuation of the rectifier-tank, said means communicating with the space inside of the tank at a place between the precooling chamber and the condensing chamber.

6. A evacuated metal-tank mercury-arc rectifier having a main tank portion having an opening in the center of its bottom, a plurality of anodes insulatedly suspended there-

within around the center portion, a liquid-mercury cathode member insulatedly attached and hermetically sealed to the bottom of the main tank portion, around the central opening therein, a cylindrical baffle supported centrally within the main tank portion and clear of both the top and the bottom of the tank, and clear of the anodes and the cathode, an annular baffle extending from the top of said cylindrical baffle to the vicinity of the side walls of said main tank portion, said annular baffle sloping somewhat downwardly from said cylindrical baffle and being above the bottoms of the anodes, and cooling means for said main tank portion, said cooling means being so disposed as to admit of a substantially unrestricted vapor flow up through the cylindrical baffle and out over the annular baffle.

7. The invention as defined in claim 6, characterized by said cooling means comprising means for conducting a cooling medium into contact with said cylindrical baffle.

8. The invention as defined in claim 6, characterized by said cooling means comprising means for conducting a cooling medium into contact with said cylindrical baffle, and a second, smaller, similarly cooled cylindrically disposed cooling member within said cylindrical baffle.

9. The invention as defined in claim 6, characterized by said cooling means comprising a smaller, cylindrically disposed member within said cylindrical baffle, and means for conducting a cooling medium into contact with the walls of said smaller, cylindrically disposed member.

10. An evacuated metal-tank mercury-arc rectifier having a main tank portion having an opening in the center of its bottom, a plurality of anodes insulatedly suspended therewithin around the center portion, a liquid-mercury cathode member insulatedly attached and hermetically sealed to the bottom of the main tank portion, around the central opening therein, cooling means for said main tank portion, said cooling means comprising a cylindrically disposed cooler supported centrally within the main tank portion and clear of both the top and the bottom of the tank, and clear of the anodes and the cathode, an annular baffle extending from near the top of said cylindrically disposed cooler to the vicinity of the side walls of said main tank portion, said annular baffle sloping somewhat downwardly from said cylindrically disposed cooler and being above the bottoms of the anodes, and an evacuating pumping means for the rectifier.

In testimony whereof, we have hereunto subscribed our names this 31st day of December, 1929.

ALFRED SIEMENS.
MORITZ SCHENKEL.
